UNITED STATES PATENT OFFICE

2,554,336

VARIABLE COMPRESSION RATIO INTERNAL-COMBUSTION ENGINE

Herbert J. Kratzer, St. Louis, Mo.

Application April 25, 1947, Serial No. 743,751

4 Claims. (Cl. 123—48)

1

The invention relates to internal combustion engines and more particularly to variable compression ratio engines of the kind described in Patent No. 2,399,276, issued April 30, 1946 to the present applicant.

The engine described in the above patent has a movable head to vary the cylinder volume for the more efficient combustion of fuel of approximately a given octane rating, and the compression ratio is varied automatically throughout a single range of head movement to compensate for different throttling effects. Different throttling may be due to manual throttling, decreased air density at higher altitudes, or throttling incidental to high engine speed. Any of these throttling effects starve the cylinders, i. e., results in the fuel charge being insufficient for an efficient compression pressure.

The main object of the present invention is to vary the operative ranges of compression ratios of a variable compression ratio engine to economically employ fuels of different octane ratings under the operating conditions mentioned above and, in addition, to compensate for temperature changes.

Another object is to readily vary the operative range of compression ratios by a conveniently located manual control.

Another object is to employ combustion chamber pressures to directly and automatically vary the combustion chamber volume of respective cylinders within a given range so that the combustion chamber volume approximately corresponds to the instant volumetric efficiency of the refueling operation.

Another object is to provide the engine with simple means to adjust the combustion chamber volume of each individual cylinder, independently of the other cylinders, to compensate for manufacturing variations, carbon deposits, wear or other factors producing unequal combustion chamber performance.

Another object is to automatically select a predetermined minimum compression ratio for the duration of the engine starting operation.

Another object is to maintain all engine spark plug electrodes at the desired temperature during all operations, except at starting, of the engine by immersing the plug porcelains in an insulating coolant fluid, such as oil from the engine crank case, and to maintain this coolant fluid at a temperature sufficient to boil off condensation products and thus recondition the fluid and preserve its dielectric properties.

Another object is to position the spark plugs

2

between the intake and exhaust valves and substantially centrally of the combustion chambers, irrespective of the prevailing compression ratio, to provide for reliable ignition and minimum flame travel.

Another object is to provide for the reliable ignition of economical fuel mixtures due to a minimum degree of new charge dilution with hot residual combustion chamber gases especially at idle and light torque loads.

Another object is to cause turbulence within the combustion chambers to insure thorough mixing of the combustion chamber gases before ignition and to increase flame speed after ignition.

Another object is to cause turbulence during flow of combustion chamber gases to cylinder bores after ignition to facilitate combustion of the gases early in the expansion stroke.

These and other objects will be apparent to those skilled in the art from the following description and accompanying drawings, in which:

Figure 1 is a plan view of an internal combustion engine constructed according to the invention.

Figures 2 and 3 are detail vertical transverse sections drawn to enlarged scale and taken approximately on the lines 2—2 and 3—3, respectively, of Figure 1.

Figure 4 is a detail horizontal section taken approximately on the line 4—4 of Figure 3.

An internal combustion engine constructed according to the invention comprises a plurality of working cylinders 1 such as may be formed, for example, in a single block 1a. Each cylinder has a reciprocating piston 2 connected by a rod 3 to the engine crankshaft (not shown). A conventional intake valve 4 and adjacent exhaust valve 5 are associated with each cylinder 1.

A cylinder head 8 is mounted on block 1a and forms a water jacket with outer side walls 9. A vertical cylindrical bore 10 through the head is above and partially overlaps each working cylinder 1 but is offset towards its associated valves 4 and 5. Slidable in each bore is an inverted head piston 11. The bottom face of head 8 is recessed over valves 4 and 5 to form pockets 4a and 5a (Figure 4). The bottom face of head piston 11 is recessed to form a pocket 11a. Pockets 4a, 5a and 11a form the major portion of the cylinder combustion chamber 7, the walls of which converge towards the remote side of the working cylinder to form

a restricted passageway 1a into the cylinder and, as so shaped, increase turbulence thereby promoting more complete combustion as early in the expansion stroke as possible.

Each head piston 11 is connected by a link 12 and pin 13 to a rocker arm 15 keyed to shaft 16 journalled in bearings 17 on head 8. One rocker arm 15 has an extension 18 provided at its free end with an adjustable pin 19 engaging a saddle 20 on the upper end of a helical coil spring 21 seated in the bottom of a hollow inverted piston 22 slidably in a spring cylinder 23 at the side of cylinder head 8. Preferably spring cylinder 23 is mounted on a bracket 24 including side walls and forming a pocket 33 for the purpose explained below.

During normal engine operation, the positions of head pistons 11 are determined by the sum of the pressures in all working cylinders 1 and by the thrust of compression spring 21 which resists and balances the working cylinder pressures. With small crankshaft torques, the sum of the pressures in working cylinders 1 is relatively small permitting spring 21 to move head pistons 11 downwardly in cylindrical bores 10 and decrease the combustion chamber volume to provide higher compression ratios. At large crankshaft torques, the sum of the pressures in working cylinders 1 is relatively large so that head pistons 11 move upwardly while compressing spring 21 and provide lower compression ratios due to the enlarged combustion chambers. This automatic determination of compression ratios provides for the optimum compression ratio at any prevailing speed-torque output of engine and compensates for barometric variations.

Oil from the crankcase is pumped through conduits 25, 25a in a block 27, into spring cylinder 23 below spring piston 22 and piston 22 is raised from the solid line position shown in Figure 2 to other positions as indicated by the broken lines in Figure 2. The lower end of spring 21 is raised and its tension is increased, whereby head pistons 11 move downwardly in cylindrical bores 10 against the prevailing working cylinder pressures and decrease the volume of the combustion chambers to increase the compression ratios. The position of spring piston 22 in spring cylinder 23 is determined by a valve sleeve 26 slidably mounted in block 27 and extending upwardly into spring cylinder 23 and into a dome-shaped portion 28 of spring piston 22. The upper end of valve sleeve 26 is slotted at 30. Valve sleeve 26 may be raised or lowered relative to spring piston 22 by an arm 29 pivoted in block 27 and link connected to valve sleeve 26. Spring piston 22 automatically moves to a position in spring cylinder 23 at the upper end of valve sleeve 26 and uncovers the lower portions of slots 30 so that excess oil pumped into spring cylinder 23 escapes through slots 30 and flows through the interior of valve sleeve 26 into a cavity 27a in block 27 and through a conduit 31 to the crankcase.

Spring cylinder 23 has ports 32 in its upper sides so that oil leaking past spring piston 22 is returned to the crankcase through pocket 33, drain 34, cavity 27a and conduit 31.

The most economical compression ratio for a particular fuel, irrespective of its octane rating, is the highest compression ratio which provides for smooth engine operation without knocking as evidenced by audible pinging. The engine may be economically adapted to fuel of any octane rating by operating lever 29 manually, preferably from the dash of the car, to provide

maximum tension of spring 21 without causing the engine to knock.

For fuels of low octane rating, spring piston 22 is lowered in spring cylinder 23 and the tension of spring 21 is decreased to operate the engine in a range of decreased compression ratios. For fuels of high octane rating, spring piston 22 is raised in spring cylinder 23 and the spring tension is increased to operate the engine in a range of increased compression ratios.

A rib 43 on head 8 engages an adjustable screw 44 at the end of an extension 42 rigid with one of the rocker arms 15 and limits downward movement of head pistons 11 and provides a maximum desired compression ratio for combustion chambers 7. An adjustable stop 40 supported by a bracket 41 attached to head 8 engages the end of extension 42 and limits upward movement of head pistons 11 and provides a minimum desired compression ratio for combustion chambers 7. In the event spring 21 breaks, the engine would continue to function as a conventional engine at the minimum compression ratio. The maximum and minimum compression ratio stops preferably are adjusted to provide for a plurality of ranges of normal operating compression ratios for fuels of various octane ratings.

When the ignition circuit is opened and the engine is stopped, a plug valve 35 is moved to open position by an arm 35a, as shown by the solid lines in Figure 2, to quickly drain oil from spring cylinder 23 below spring piston 22 through conduit 25a, cavity 27a and conduit 31 to the crankcase, whereupon spring piston 22 moves rapidly to the solid line position shown in Figure 2, head pistons 11 move downwardly until screw 44 engages stop 43, and spring 21 extends substantially to its free length.

During starting of the engine, when the crankshaft is being turned slowly by the starter, and before any cyclic firing, only compression pressures contract spring 21 which offers but little resistance to upward movement of head pistons 11 which move approximately midway between maximum and minimum combustion chamber volumes as determined by stops 40 and 43. Initial ignition in combustion chambers 7 increases the sum of the combustion chamber pressures sufficiently to move head pistons 11 upwardly to their maximum combustion chamber volume. After the motor operates through a few revolutions, intake manifold pressures and resulting combustion chamber pressures decrease, whereupon head pistons 11 are moved downwardly by spring 21 approximately midway between maximum and minimum combustion chamber volumes. With further operation of the engine, spring piston 22 is raised in spring cylinder 23 by oil under pressure from the engine lubricating system until slots 30 in valve sleeve 26 are uncovered. Displacement of spring 21 moves head pistons 11 downwardly decreasing the combustion chamber volume until the spring tension is balanced by the sum of the cylinder pressures and the engine operates in the normal manner described above.

Each rocker arm 15 comprises a pair of opposed elements 15a and 15b clamped together on opposite sides of shaft 16 by a pair of eye bolts 14 and 14a. Elements 15a are keyed to shaft 16. Eye bolts 14 are connected by pins 13 and links 12 to head pistons 11 which may be adjusted individually relative to one another to provide a desired compression ratio in the associated working cylinder relative to the compression ratio in

other working cylinders. The volume of a compression chamber 7 may be decreased by loosening the nut on eye bolt 14 and tightening the nut on eye bolt 14a to shift element 15b about shaft 16 relative to keyed element 15a whereby head piston 11 is moved downwardly a short distance in head bore 10. The nuts on eye bolts 14 and 14a then may be locked to retain head piston 11 in adjusted position.

Another of the arms 15 has an integral extension 50 provided with a bifurcated free end connected to one end of a link 51 by a pin 51a. The opposite end of link 51 is connected by a pin 51b to a dash pot piston 53 slidably mounted in an oil-filled dash pot cylinder 55. Cylinder 55 is attached to head 8 by webs 52. Dash pot piston 53 has a spiral Acme thread-shaped depression 54 about its circumference forming an elongated passageway bypassing the piston, thus enabling gradual movement of the dash pot piston in the dash pot cylinder. A plurality of equally spaced conduits 56 connect respective ends of cylinder 55 through upper and lower ports 57 and 58. Upper ports 57 normally are closed by the skirt portion of a cap 59 mounted rotatably on cylinder 55 and having apertures 60 through the skirt portion movable into registry with upper ports 57 to allow oil to flow freely through conduits 56 whenever more rapid adjustment of piston 53 is desired. The dash pot damps intercyclic firing impulses transferred to shaft 16 during normal engine operation so that the algebraic sum of the rapidly changing cylinder pressures will be counterbalanced by spring 21 whereby head pistons 11 and shaft 16 will move only when a change in engine torque occurs.

A spring 61 urges cap 59 against stop 62 in which position the cap closes ports 57. The cap may be moved to open said ports temporarily when the starter is actuated or when the throttle is opened quickly. This opening of ports 57 is effected through link 63 which has a rod 64 leading direct to the starter (not shown). Link 63 is connected to the throttle by a dash pot unit including a chamber 65, a piston 65a thrust towards the upper end of the chamber by spring 65b and a rod 65c connected to a lever 66 pivoted on the engine. A rod 66a leads to the throttle (not shown). The pin and slot connections between link 63 and the starter rod and the throttle rod enable the link to be moved by either rod independently of the other. When link 63 is moved from the solid line position shown in Figure 4 to the dotted line position by slow movement of the throttle, oil passes piston 65a and the position of link 63 is not changed. When the throttle is opened rapidly, oil in chamber 65 cannot pass piston 65a rapidly enough and chamber 65 is moved, thus shifting cap 59 to open ports 57 and allow oil in dash pot cylinder 66 to bypass piston 53 through ports 57 and 58 so that head pistons 11 respond more rapidly to pressure changes in cylinder 1.

The space 71 between working piston 2 at the top of its stroke and the overlying flat portion of cylinder head 8 preferably is a minimum. During the last part of the compression stroke of a working piston 2, the compressed gases above the piston are finally displaced from between the top of working piston 2 and the overlying portion of cylinder head 8 through passageway 7a into combustion chamber 7 with considerable velocity approximately in the directions indicated by the arrows in Figure 3, causing desirable turbulence of the gases in the combustion cham-

ber to facilitate rapid flame travel from the spark gap through the combustion chamber as the working piston completes its upward compression stroke and starts downwardly on the expansion stroke. As the piston continues to accelerate in its downward movement, the ignited charge moves from the combustion chamber through the relatively narrow passageway 7a into working cylinder 1 at an increased velocity. This downwardly directed flow of ignited gas causes further turbulence in the working cylinder and facilitates the continued rapid combustion causing maximum expansion pressure at the time the piston and crankshaft are positioned for maximum conversion of cylinder pressure into turning torque.

A spark plug 73 is threaded into the pocket portion of head piston 11 between the intake and exhaust valves so that the intake charge cools the spark gap electrodes. Plug 73 is positioned substantially centrally of the combustion chamber. The spark gap electrodes of spark plug 73 are maintained substantially at a desired temperature by immersing the plug head in coolant oil contained in head pistons 11. The oil prevents hot spots on the portion of head pistons 11 forming parts of the combustion chamber walls by convecting heat from these parts to the side walls of head pistons 11 for transmission to water jacketed head bores 10. The oil is maintained at a temperature sufficiently high to boil off condensation products and thus recondition the oil and maintain its dielectric properties to prevent short-circuiting over the plug porcelains. Oil from the crankcase may be circulated continuously through head pistons 11 as part of the oil filter system for continuously reconditioning the oil. High tension ignition cables 75 connect the immersed spark plugs 73 to the distributor (not shown).

40 The skirts of pistons 11 always extend above the sides of head bores 10 to prevent oil seeping into combustion chambers 7 when the engine is stopped. A cover (not shown) may be provided for excluding dust and other injurious matter from the mechanism described. A raised rib 45 along the top periphery of head 8 directs spilt oil to drain into pocket 33 to be returned to the crankcase.

The details of the construction may be varied substantially without departing from the spirit of the invention, and the exclusive use of those modifications coming within the scope of the claims is contemplated.

What is claimed is:

55 1. In an internal combustion engine, a cylinder, a movable wall associated with said cylinder to change its compression ratio in accordance with cylinder pressures, a spring resisting the cylinder pressures and automatically positioning said wall during normal engine operation to determine the compression ratios within a predetermined range, a seat for said spring, hydraulic means to move said seat during engine starting operation to change the pressure of said spring, and manually adjustable means for controlling said hydraulic means to vary the seat position to change the spring pressure and thereby change the operative range of compression ratios.

70 2. In an internal combustion engine, a cylinder, a movable wall associated with said cylinder to change its compression ratio in accordance with cylinder pressures, a spring resisting the cylinder pressures and automatically positioning said wall during normal engine operation to determine the compression ratios within a predetermined range,

a piston seating said spring, a spring cylinder slidably receiving said piston, a hydraulic device actuated by fluid pressure, supplied by the normal operation of the engine, to move said spring seating piston in said spring cylinder to change the thrust of said spring, said device including a manually actuated positively adjustable ported sleeve control for varying the position of the spring seating piston and thereby varying the operative range of compression ratios.

3. In an internal combustion engine, a plurality of cylinders, a movable wall associated with each cylinder and movable inwardly and outwardly of said cylinder to change its compression ratios, means to resist the sum of the prevailing cylinder pressures and to automatically position said walls in unison during normal engine operation to determine the compression ratios, a pulsation eliminator to damp movement of said walls inwardly and outwardly of said cylinders, and means to render said pulsation eliminator substantially inoperative during rapid engine acceleration and during engine starting.

4. In an internal combustion engine, a cylinder, a movable wall associated with said cylinder to change its compression ratio in accordance with cylinder pressures, a spring resisting the cylinder pressures and automatically positioning said wall during normal engine operation to determine the compression ratios within a predetermined range, 15 a seat for said spring, mechanism actuated automatically by the engine during its starting to move said seat to change the pressure of said spring, and manually adjustable means to vary the seat position to change the spring pressure and to change the operative range of compression ratios.
